RACK FOR PAPER BAGS OR THE LIKE

Stanley W. Peterson, Racine, Wis., assignor of one-fourth to Andrew J. Cottone, Racine, Wis., and one-fourth to Alex F. Skover, La Crosse, Wis.

Filed May 12, 1961, Ser. No. 116,226

3 Claims. (Cl. 211—49)

This invention relates to paper bag racks, and more particularly it relates to a bag rack of the type which can be mounted on a cabinet door or the like.

It is an object of this invention to provide an improved rack for holding a supply of paper products such as bags or the like and to do so in a manner so that the bags can be readily inserted into the rack and withdrawn therefrom.

A more specific object of this invention is to provide a paper bag rack which permits easy access to the bags in the rack, and which has a large capacity for retaining a quantity of bags, and which is nevertheless simple and inexpensive in its manufacture and in its mounting on a cabinet door or the like.

Still another specific object of this invention is to provide a paper bag rack which automatically causes the bags to be held therein by a wedging action which is effective in conjunction with the tendency of a folded bag to expand.

Still another object of this invention is to provide a bag rack which can be stacked in a plurality of racks in a very minimum space for the purpose of conserving store counter space or the like, and in accomplishing this particular object, the racks of this invention can be readily nested in a compact relation for the feature mentioned.

Other objects and advantages will become apparent upon reading the following disclosure in light of the accompanying drawings, wherein:

FIG. 1 is a top plan view of a rack of this invention.

FIG. 2 is a front elevational view of the rack.

FIG. 3 is a side elevational view of the rack and showing another rack stacked therewith in dotted lines.

FIG. 4 is a reduced perspective view of the rack shown in position on a cabinet door or the like.

The same reference numerals refer to the same parts throughout the several views.

The drawings show the rack to consist of an upper U-shaped piece generally designated 10 and made of a wire material of suitable diameter and rigidity. Thus the member 10 consists of an intermediate portion 11 and two extending or leg portions 12 arranged so that the portion 11 will of course be spaced from the door such as the door 13 shown in FIG. 4. The ends of the member 10 are provided with loops 14 which present openings 16 through which screws or other fasteners (not shown) would of course pass for the common purpose of securing the rack to the door 13.

Four wire members or struts 17 are suitably attached in spaced-apart positions along the upper portion 11 to depend therefrom and extend downwardly to the lower portion 18 of the rack. Here it will be noted that the members 17 extend from the outer surface of the member 11 and they extend downwardly to the outer or lower surface of the member 18. A significant feature of the rack construction resides in the angularity and configuration of the members 17 and here it will be noted that the upper portion 19 of each of the members 17 is shown to extend in a straight extent downwardly to an arcuate portion 21 which continues to the point of connection with the lower member 18.

At this time it will also be noted that the member 18 is provided with a loop 22 which presents an opening 23 through which a screw or other fastener (not shown) can be passed for securing the rack to the door 13. It will

2

further be noted that the length of the member 18 is less than the length of the upper member 10 and this feature is significant for the purpose of stacking the racks as shown in FIG. 3 by the inclusion of the dotted rack superimposed on the solid line rack of FIG. 3. Still further, it will be seen in FIG. 1 that the lower member 18 is slightly angled between the two opposite half lengths so that upon entering and securing the loop 22 against the door 13, the point indicated 24 in FIG. 1 will of course be securely forced against the door 13 when the loop 22 is drawn tightly against the door 13 by the screw mentioned.

As previously mentioned, the angularity and shape of the members 17 is significant in securing the bag in the rack and it will thus be understood that folded paper bags or the like can be readily inserted through the piece 10 and into the rack to be disposed between the members 17 and the door 13 in the obvious manner. However, due to the angularity and curvature of the members 17, the bags will be automatically and readily secured in the rack as they tend to expand between the door 13 and the smaller confines of the rack at the lower ends of the members 17. This securely holds the bags in the rack as mentioned. This is true since the bags are of course pushed downwardly into the rack to the lower-most position depending upon the numbers and therefore the thickness of the bags, so that if only a few bags are placed in the rack, they would be pushed down in the rack until they engage the portions 21 of the members 17 and this would bring the bags into snug contact with the door 13 so that the bags would not fall out the open sides of the rack. Also, if a greater number of bags are to be placed in the rack, then they would be perhaps higher in the rack, and therefore in line with the upper portion 19 of the members 17 where greater capacity of the rack is provided. Also, the particular construction described permits easy insertion and withdrawal of the bags with respect to the rack.

Another particular feature of the construction is as mentioned, namely that the rack has no side pieces extending, for instance, between the legs 12 of the member 10 and the lower end of the rack, and therefore the rack can be readily nested one above the other in a very compact relation for the purpose of conserving display space. This of course becomes particularly important in present-day merchandising and it therefore permits that the racks be made of a substantial size so that a large quantity of bags can be held and large size bags can be held.

It will thus be understood that a rack for retaining paper products is provided and it will be particularly noted that the free ends, that is the hook portions 14, of the upper members leg 12 and the lower member 18 are in one upright plane while of course the intermediate portion 11 of the member 10 is in a vertical plane offset from the one common upright plane mentioned. Then the interconnecting members 17 extend between the intermediate portion 11 and the lower member 18 at an angle oblique to the upright plane throughout the entire length of the members 17 and thus a lesser space is provided from the upper end of the rack down to the lower end of the rack and therefore the paper products can be wedged into the rack and retained therein without requiring that there be any side members on the rack and therefore a simplified rack is provided and the stacking feature can be accomplished as shown in FIG. 3. In this connection it will of course be understood that the racks can be laid on a store shelf with the members 17 down and the legs 12 extending upwardly so that the dotted rack shown in FIG. 3 would of course be laid over the lower solid-line rack and a number of racks could thus be stacked in this manner. It will still further be recognized that the legs 12 are angled downwardly from the upper end of the members 17 and thus the stacking of the racks progresses in virtually a vertical direction even though the racks are

offset as shown in FIG. 3. Thus an acute angle is formed between the legs 12 and the members 17 as shown in FIG. 3.

It will further be noted that the interconnecting members have a short upper end 26 which is shown to be disposed parallel to the plane of the loops 14 and 22 and this is of course at an acute angle with respect to the upper member 12 as described. Thus when the racks are stacked one above the other with the interconnecting members 17 disposed in the lower-most position on the shelf or the like, the upper end 26 and the lower end 21 prevent the racks from sliding out of the vertically stacked position and this is as indicated in FIG. 3. In other words, both ends 21 and 26 extend upwardly from the lower horizontal portion 19 of member 17 to prevent sliding which would upset the stacked racks.

Also, the bottom curvature 21 further serves the purpose of causing the bags to actually ride up or rise in the rack when the user inserts a hand into the rack and presses the bags toward the member 17 and the bags are then caused to follow the angle or curvature of the portion 21 and rise in the rack as mentioned so that the greater capacity of the rack at the upper end is utilized and more bags can then be accommodated.

While a specific embodiment of this invention has been shown and described, it will be understood that certain changes could be made therein and the invention therefore should be limited only by the scope of the appended claims.

What is claimed is:

1. A rack for paper, comprising an upper member of a U-shape including two legs and an intermediate portion, a lower member spaced below said upper member and disposed parallel to said intermediate portion thereof, said members including means for mounting same on an upright support with said upper member in a horizontal plane, the free ends of said legs and said lower member being disposed on a common upright plane and with said intermediate portion of said upper member being spaced from said support and with said lower member being adjacent said support, and interconnecting J-shaped members disposed inwardly from said legs and extending between said intermediate portion and said lower member at an angle oblique to said plane to present a progressively lesser space from said support in the entire extent of said J-shaped members from said upper member to said lower member for securely holding different thicknesses of said paper along the length of said J-shaped members.

2. A wire rack for paper and arranged for stacking on a horizontal support, comprising an upper member of a wire material and disposed in a U-shape including two legs and an intermediate portion, a plurality of interconnecting members of a wire material attached to and spaced along said intermediate portion and depending therefrom in an upper portion and a straight central portion and a

lower portion and with the latter disposed laterally beyond said interconnecting members, a lower member of a wire material disposed in the vertical plane of the free ends of said legs and therebelow and parallel to said intermediate portion and extending transverse to said interconnecting members and being attached to the lower ends thereof, said upper portion and said lower portion being offset from the straight line of said central portion and directed inwardly toward said upper member and said lower member, respectively, adapted for nesting of one said rack on top of another said rack when said racks are stacked on said horizontal support, and for said lower member to present a decreasing space downwardly therewith along with said vertical plane for securely holding different thicknesses of said paper, and means on said upper member and said lower member for attaching said rack to an upright support.

3. A wire rack for paper and adapted for compact stacking of a plurality of racks and each said rack arranged for securely holding quantities of paper, comprising an upper member of a wire material and disposed in a U-shape including two legs and an intermediate portion of a selected length and being disposed in a horizontal plane, a plurality of interconnecting upright members of a wire material attached to and spaced along said intermediate portion for a distance less than said selected length and depending therefrom at an acute angle with respect to said horizontal plane and said legs and with the latter disposed laterally beyond the upright planes of said upright members, a lower member of a wire material disposed along the vertical plane common to the free ends of said legs and therebelow and extending parallel to said intermediate portion of said upper member and transverse to said interconnecting upright members and being attached to the lower ends thereof, said interconnecting upright members being disposed to be directed toward said lower member in a manner to provide a progressively diminishing space between said interconnecting members and said vertical plane in the downward direction, means on said upper member and said lower member for attaching said rack to a vertically disposed support, said rack being devoid of any members in the space extending from said upright members to beyond said vertical plane and interconnecting said upper member and said lower member for stacking of said racks successively in said space.
